UNITED STATES PATENT OFFICE.

WILLIAM HARRY BRASIER, OF CORPUS CHRISTI, TEXAS.

COMBINATION SAFETY-RAZOR AND HAIR-TRIMMER.

1,276,022.

Specification of Letters Patent. Patented Aug. 20, 1918.

Application filed May 25, 1917. Serial No. 170,929.

To all whom it may concern:

Be it known that I, WILLIAM HARRY BRASIER, a citizen of the United States, residing at Corpus Christi, in the county of Nueces and State of Texas, have invented a new and useful Combination Safety-Razor and Hair-Trimmer, of which the following is a specification.

The device forming the subject matter of this application is a tool adapted to be employed either for shaving or for hair trimming, and the invention aims to provide, in a device of this type, a reversible plate, carrying a guard and comb teeth, the plate being reversible to permit the guard to be used in connection with a blade, for shaving, and to permit the teeth to be used in connection with a blade, for hair trimming.

Another object of the invention is to provide novel means for holding the blade in operative relation to the adjustable plate.

Another object of the invention is to provide novel means whereby the plate may be held in adjusted positions with respect to the blade.

Another object of the invention is to provide novel means for assembling a handle with the head of the tool and with the plate, in such a way that the handle serves as a clamping means for holding the plate in adjusted positions with regard to the blade.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows in side elevation, a tool constructed in accordance with the present invention;

Fig. 2 is a longitudinal section taken through the head of the tool and the blade;

Fig. 3 is a transverse section taken through the head of the tool and the blade;

Fig. 4 is a plan of the reversible plate which carries the guard and the comb teeth;

Fig. 5 is a perspective view showing the head.

The device forming the subject matter of this application comprises a head denoted generally by the numeral 1 and including a flat table 2 having a transverse, elongated slot 3. The table 2 has upstanding sides 4 provided with inwardly projecting guides 5 at the inner edges of which, upstanding walls 6 are fashioned. The upper edges of the walls 6 are downwardly and forwardly inclined as shown at 7, and carry outwardly extended blade supports 8, the outer edges of which are supplied with inwardly extended, overhanging, resilient blade grips 9.

The numeral 10 denotes a plate mounted to slide forwardly and backwardly on the table 2, beneath the guides 5. The plate 10 along one edge is supplied with guard teeth 11, and along the opposite edge of the plate 10 are located comb teeth 12 which are finer than the guard teeth 11. In the plate 10 is fashioned a threaded opening 14. A blade 15 rests on the blade supports 8, which are downwardly and forwardly inclined, and is held thereon by means of the grips 9.

The numeral 16 denotes a handle provided adjacent its upper end with an abutment 17 and terminated at its upper end in a threaded stem 18. The stem 18 passes through the slot 3 in the table 2 and is threaded into the opening 14 in the plate 10. The plate 10 may be moved forwardly and rearwardly by means of the handle 16, and when the handle 16 is rotated, the table 2 is bound between the plate 10 and the abutment 17. In this way, either the guard teeth 11 or the comb teeth 12 may be held in operative relation to the cutting edge of the blade 15, it being possible to reverse the plate 10, so that either the guard teeth 11 or the comb teeth 12 are disposed in operative relation to the cutting edge of the blade 15.

Further, the blade 15 may be adjusted along the inclined blade supports 8. Owing to the adjustments above mentioned, the space between the cutting edge of the blade 15 and the guard teeth 11, or between the cutting edge of the blade and the comb teeth 12, upon the other hand, may be regulated, thereby to give either a close or a medium shave, and to regulate the length at which the hair is trimmed, when the

comb teeth 12 are disposed adjacent the cutting edge of the blade 15.

Having thus described the invention, what is claimed is:—

- 5 In a device of the class described, a head comprising a flat table having a transverse elongated slot, the table having upstanding sides provided with inwardly projecting guides, at the inner edges of which, upstanding walls are fashioned, the upper edges of the walls being downwardly and forwardly inclined, and carrying outwardly extended blade supports, the outer edges of which are supplied with inwardly extended
- 13

blade grips; a blade held between the grips and the supports; a guard plate on the table beneath the guides; and a handle abutting against the table, the handle having a reduced stem extended through the slot and threaded into the guard plate.

In testimony that I claim the foregoing as my own, I have hereto affixed my signature in the presence of two witnesses.

WILLIAM HARRY BRASIER.
